UNITED STATES PATENT OFFICE.

MICHAEL I. PUPIN, OF NORFOLK, CONNECTICUT, AND EDWIN H. ARMSTRONG, OF YONKERS, NEW YORK, ASSIGNEES TO WESTINGHOUSE ELECTRIC AND MANUFACTURING COMPANY, OF EAST PITTSBURGH, PENNSYLVANIA, A CORPORATION OF PENNSYLVANIA.

TONE-PRODUCING RADIORECEIVER.

Application filed February 10, 1916. Serial No. 77,438.

To all whom it may concern:

Be it known that we, MICHAEL I. PUPIN, a citizen of the United States, residing in Norfolk, county of Litchfield, State of Connecticut, and EDWIN H. ARMSTRONG, a citizen of the United States, residing in Yonkers, county of Westchester, State of New York, have invented certain new and useful Improvements in Tone-Producing Radioreceivers; and we do hereby declare the following to be a full, clear, and exact description of the invention, such as will enable others skilled in the art to which it appertains to make and use the same.

15 The object of this invention is the reception of continuous waves by means of a new form of tone producing apparatus in which an electrical amplifier is arranged to repeat the incoming waves at an amplitude which 20 varies periodically at an audible frequency so that the resultant electric waves produce a musical note in any ordinary receiving system. The modification in amplitude is most conveniently produced by means of a 25 vacuum tube repeater-amplifier which repeats the incoming high frequency oscillations from the antenna to the usual receiving apparatus, but which repeats only at periodic intervals or with an amplitude which 30 varies periodically with time so that the incoming oscillations of continuous amplitude are delivered to the receiver as amplified oscillations of the same frequency but periodically varying in amplitude, the period of 35 these variations being at an audible frequency.

Referring to the diagrams which form a part of this specification,

Figure 1 illustrates a means of securing 40 the required periodic variations in the amplitude of the repeated signal by means of an alternator as hereinafter described.

Fig. 2 illustrates a method of securing 45 the desired variation automatically by means of the tube itself;

Fig. 3 and Fig. 4 show methods of protecting the detector and telephone or similar translating device from the direct effect of the local frequency which may, under certain 50 conditions, produce a continuous tone in the telephone.

Referring now to Fig. 1, 1 is a vacuum tube repeater having in its output circuit an alternator 2; and 3 represents any suit-

able detecting translating device associated 55 with the output circuit of the relay as shown. In this diagram, as in the other diagrams of the drawings, the means for detecting the received signals is illustrated as a rectifying detector 16 associated with a pair of 60 telephones 17, but it will be understood that any suitable detecting means may be employed, and that when in the specification and claims we refer to an oscillation responsive device, we intend to include this 65 detecting arrangement as well as any equivalent thereof.

The production of a tone for continuous waves is accomplished as follows—It is well known that the various types of vacuum 70 tubes will reproduce at greater amplitude electric waves impressed on the exciting side of the tube and that this amplification ratio will be constant if the steady value of thermionic current through the tube is not 75 changed. Under these conditions with a tube arranged to repeat from an antenna to an ordinary receiving system continuous waves of constant amplitude impressed on the antenna will be reproduced exactly in 80 the receiving circuit. As these waves are of constant amplitude there will be no appreciable response in the telephones. If, however, the thermionic current is varied periodically at some audible frequency the amplification ratio of the tube will vary periodically at the same frequency so that continuous oscillations of constant amplitude in the antenna are repeated to the receiving circuit as amplified oscillations of periodically 85 varying amplitude. By varying the thermionic current at a suitable frequency the signal produces any desired musical tone in the 90 telephones.

The variation in the thermionic current 95 and consequently in amplifying ratio, may be obtained in several other ways, as, for instance, heating the filament by an alternating current or, in the three-electrode tubes, by connecting the alternator in the grid circuit so that it varies the wing current indirectly by varying the grid potential. The manner of operation of any of the methods is obvious from the foregoing explanation. It should here be noted that the receiver operates most effectively when the thermionic current, at those times when it is reduced to its lowest value, approaches as nearly as pos- 100 105

sible to zero. For this reason the use of alternating current to heat the filament is not as effective as one of the other methods, as the temperature of the filament does not vary between sufficiently wide limits when the frequency of the heating current is within the range of good audibility.

The amplifying ratio may be varied automatically by the tube itself and the alternator dispensed with. This result is accomplished by the system of Fig. 2 in which the tube 4 is arranged with a reaction circuit 5, 6, 7, 8 which causes the system to oscillate continuously at a suitable low frequency. This frequency is determined by the constants of the transformer 6, 7 and the capacity of the condensers 5, 8. By adjustment of these condensers the local frequency is regulated to produce a variation in the thermionic current of any desired audible frequency. The behavior of the rest of the system in regard to the signalling frequency is the same as for the system of Fig. 1.

It is advisable to protect the receiving circuits from the effects of the local frequency which tends to produce a continuous tone in the telephone and a method of accomplishing this is shown by Fig. 3. Two tuned paths 10-11 and 12-13 selective respectively to the low and high frequencies are connected in parallel as shown. The two frequencies are thereby separated and the receiving circuit effectively shielded. As an additional precaution the adjacent ends of the transformer 11-13 may be grounded as illustrated to guard against capacity currents between them through the telephones to earth. An improved substitute for the selective path 12-13 is illustrated by Fig. 4 in which the output circuit of the repeater is connected with the receiving apparatus by means of a selective path consisting of an artificial line 15 of the type illustrated in the drawing. The line consists of several equal elements, each comprising a capacity 18 shunted by an inductance 19, the inductance and capacity of each element being so adjusted that the element fulfills the conditions of resonance

for a frequency about 50% higher than the frequency of the incoming signalling waves. Such a line will transmit efficiently the high frequency of the incoming waves but will wipe out completely the local low frequency.

What we claim is:

1. A receiver for continuous high-frequency electric waves comprising a wave conductor, an electrical repeater, including a means for producing a local frequency, an oscillation-responsive device connected to the output circuit of the repeater through an artificial line which has a high attenuation constant for the local frequency and a low attenuation constant for the signalling frequency, said artificial line being composed of a plurality of like units, each unit comprising two impedances of unlike reactance and all of said units being similarly connected, said repeater being arranged to repeat electrical currents in the wave conductor into the oscillation-responsive device at a periodically varying amplitude.

2. In a radio receiving system, a receiving circuit, a vacuum-tube device coupled thereto, means associated with said device for producing a low-frequency modulation, an oscillation-responsive device and a high-pass radio-frequency filter between said oscillation device and said modulating means, comprising a plurality of like units, each of said units having a plurality of impedances of unlike nature, impedances of like nature being similarly situated in the several units.

3. In a radio signaling system, a vacuum-tube device, a translating device and a filter coupling them, said filter including a plurality of like units, each unit comprising two reactances of opposite sign, all the reactances of one sign being connected in series and all those of the other sign in parallel, whereby the units form a chain extending the length of the filter.

In testimony whereof we affix our signatures.

MICHAEL I. PUPIN.
EDWIN H. ARMSTRONG.
